UNITED STATES PATENT OFFICE.

CHARLES E. STANTON, OF HAMPTON, VIRGINIA.

WINDOW-SCREEN.

992,284.

Specification of Letters Patent.

Patented May 16, 1911.

Application filed July 6, 1910. Serial No. 570,628.

To all whom it may concern:

Be it known that I, CHARLES E. STANTON, a citizen of the United States, residing at Hampton, in the county of Elizabeth City 5 and State of Virginia, have invented a new and useful Window-Screen, of which the following is a specification.

This invention relates to metallic window screens and has for its object to provide a 10 slideable screen mounted in a novel manner within guides provided therefor and which are adapted to be secured to the outer guide strips of the window casing.

Another object is to provide a screen made 15 up of metal tubes having efficient means for securely attaching the wire fabric thereto without the necessity of employing rivets, screws or other similar fastening devices.

A still further object is to provide a window screen made up of upper and lower slideable sections either or both of which can be 20 readily removed from the guides provided for them, means being employed for holding the frames of the two sections out of contact.

A further object is to provide a screen the sections of which are arranged to cause the metal fabrics thereon to contact and thus 25 positively prevent flies from passing between the two sections.

Another object is to provide a lower screen section having an inset portion upon the lower rail thereof adapted to receive shutter fasteners and the like, means being 35 provided in said lower rail whereby moisture may readily drain under the rail.

With these and other objects in view the invention consists of certain novel details of construction and combinations of parts 40 hereinafter more fully described and pointed out in the claims.

In the accompanying drawings the preferred form of the invention has been shown.

In said drawings:—Figure 1 is a perspective view of the screen in position within a window casing, said screen being viewed from the outside of the window. Fig. 2 is a central vertical section through the screen and casing and showing the relative positions of the screen and window sashes. Fig. 3 is an enlarged transverse section through the window casing and screen, said section being taken through the side rails of both screen sections. Fig. 4 is an elevation 55 showing the inner face of the lower portion of the lower screen section, a portion of said

section being broken away. Fig. 5 is an enlarged section through one side rail of each section of the screen. Fig. 6 is an enlarged elevation of one corner portion of the lower 60 screen section. Fig. 7 is a perspective view of one of the side rails of a screen section and showing a bearing spring thereon. Fig. 8 is a vertical section through the lower rail of the bottom screen section. Fig. 9 is an 65 enlarged section through a portion of said rail and showing a drain opening in the bottom edge thereof. Fig. 10 is an enlarged section through one of the fabric holding tubes used in connection with each rail of 70 the screen. Figs. 11 and 12 are transverse sections through the guides in which the screens are mounted to slide.

Referring to the figures by characters of reference A designates a window casing having upper and lower sashes, B and C mounted therein in the usual manner. Secured to the outer guide strips a of the casing A are guides 1 and 2 each of which is formed of a thin strip of metal bent to form a longitudinal channel extending throughout the height of the window opening in the casing. The channel in the guide 1 is much deeper than the channel in the guide 2 and each of the guides has a central longitudinally extending guide rib 3 within the channel and which is for the purpose hereinafter set forth. It is to be understood that these guides 1 and 2 may be attached to the strips a in any suitable manner, as by means of 85 90 nails, screws or the like.

The screen consists of two sections slidably mounted within the guides 1 and 2, the upper section, which has been indicated at D, being mounted between the ribs 3 and 95 the outer flanges of the guides 1 and 2, while the lower screen section, which has been indicated at E is mounted between the ribs 3 and the inner flanges of the guides. The section E consists of a sheet metal frame 100 made up of side rails 4 and top and bottom rails 5. Each of these rails consists of a strip of sheet metal bent to form a substantially oblong tube, the ends of the said tube being beveled and held together by corner 105 irons or brackets 6 which are soldered, riveted or otherwise secured to the rails. The longitudinal edges of each strip forming a rail of the frame are extended inwardly along diverging lines and are spaced 110 apart so as to form longitudinal slots 7 from which the said inturned edge portions

8 extend. All of the slots are formed in the inner faces of the rails of the upper section of the screen and the wire fabric 9 used in connection with the frame, has its edge portions projecting into the slots 7 and held therein by a tube 10 preferably formed of a rolled strip of spring metal or by a wire. This tube or wire is bent to form a rectangular frame and is forced into the slots 7 and presses the edge portions of the fabric 9 thereinto and where a tube is used it expands against the said fabric and the inturned edge portions 8 so as to securely hold the fabric in position on the frame.

15 One of the side rails of the frame E has bow springs 11 secured to the side faces thereof, these springs being attached at their centers to the rail by means of rivets or the like. The terminal portions of the springs 20 are curved and are adapted to slide within the guide 1 so as to press the opposite side rail of the section D tightly against the intermediate wall of the guide 2. In other words these springs 11 constitute yielding 25 runners which serve to hold the frame of the upper section properly seated under normal conditions within the guide 2. The lower screen section E is also formed of metal frame having wire fabric stretched thereon.

30 This frame consists of side and top rails 12 similar to the rails 4 and 5 and having their meeting ends beveled and connected together by means of corner irons 13. These rails are also provided with longitudinal slots 35 similar to the slots 7 for the reception of the edge portions of the wire fabric 14, the said slots being adapted to receive holding tubes such as shown in section in Fig. 10.

35 The lower rail 15 of the bottom section E differs from the lower rail 5 in that it has a sheet metal apron 16 extending throughout the length thereof and projecting downwardly therefrom, the said apron having its end portions in the same plane with the outer face of the rail 15 while the lower intermediate portion of the apron is pressed inwardly to form a hood 17, into which shutter fasteners and the like may move without interference from the screen. Lifts 45 or hand-holds 18 may be connected to the apron at points adjacent the end of the hood 17 to facilitate raising and lowering the lower section E of the screen and the lower edge of the hood may be recessed as indicated at 19 so as to permit water to drain under the screen should it be deposited on the sill of the casing A.

50 When it is desired to place the screen in position within the casing A, the guides 1 and 2 are secured to the strips α , it being understood that these guides extend throughout the length of the strips α . The upper screen section D is then placed with the springs 11 thereon within the guide 1 and 55 between the rib 3 therein and the outer flange of the guide. The springs are then compressed sufficiently to permit the opposite side of the section D to be brought between the flanges of the guide 2, after which the springs 11 are permitted to relax and 70 will shift the section into the guide 2 and between the rib 3 therein and the outer flange of the guide. The lower section E can then be placed within the guide in the same manner and with the hood 17 projecting inwardly. Should it be desired to raise the lower section, it is merely necessary to pull upwardly on the lifts or hand-holds 18 whereupon the said section will be caused to slide within the guides, the springs 80 on the section holding the same in frictional engagement with the guides to a sufficient extent to maintain the section at any elevation to which it may be moved. The upper section D can be pulled downwardly 85 in the same manner as the upper sash of a window and the springs on this upper section will hold it against movement after it has been adjusted to any position desired. Should any water drop onto the sill between 90 the hood 17 and the inner or lower sash, C, it will be free to drain outwardly through the recesses or openings 19 in the bottom edge of the hood.

95 It will be noted that each section of the screen is formed entirely of metal and wire fabric and is very simple, durable and compact. It is unnecessary to utilize screws or other fastening devices for the purpose of holding the parts assembled as the rails constituting each frame can be soldered together or can be held together by the corner irons which are soldered thereto. The expandible tubes 10 or the wires constitute efficient 100 means for holding the fabrics 9 in position on the frames and constitute an attractive finish to each rail of the screen inasmuch as each tube, coöperating with the rail, conceals the edge portion of the wire fabric and presents a rounded surface or bead which gives 105 a finished appearance to the article.

110 While the screen sections are mounted within the guides 1 and 2, the ribs 3 serve to hold the rails thereof out of contact. It will be noted, also, by referring particularly to Fig. 5 that the wire fabric of the upper screen is mounted on the inner faces of the frame of the section D while the fabric on the lower section E is mounted on the outer faces of the rails of said sections. The said fabrics of the two sections will thus lie close together or in contact at all times, and thus prevent flies from passing between the two sections. The various parts can be of any 115 sizes and proportions desired; the members of the frame being preferably $1\frac{5}{8}$ " by $1\frac{1}{4}$ ".

120 It is of course to be understood that various changes may be made in the construction and arrangement of the parts without departing from the spirit or sacrificing any 125 130

of the advantages of the invention as defined in the appended claims.

What is claimed is:—

1. The combination with a screen and guides channeled longitudinally and having a central longitudinal guide rib within each channel, of frames removably and slidably mounted within the guides and spaced apart by the ribs, and elastic means carried by each of the frames for holding one side of each frame in frictional engagement with one of the guides.
2. A screen including top bottom and side rails, and an apron extending downwardly from the bottom rail and having a blind fastener receiving hood, there being drain openings in the edge portion of the hood.

In testimony that I claim the foregoing as my own, I have hereto affixed my signature in the presence of two witnesses.

CHARLES E. STANTON.
